Attorney.

UNITED STATES PATENT OFFICE.

THOMAS SCHOLES, OF CHICAGO, ILLINOIS.

COAL-ASH SIFTER.

SPECIFICATION forming part of Letters Patent No. 366,887, dated July 19, 1887.

Application filed January 26, 1887. Serial No. 225,605. (No model.)

To all whom it may concern:

Be it known that I, THOMAS SCHOLES, of Chicago, county of Cook, and State of Illinois, have invented certain Improvements in Coal-
5 Ash Sifters, of which the following is a specification.

My said invention will be hereinafter more fully described with reference to the accompanying drawings, in which—

10 Figure 1 represents a perspective of a coal-ash sifter embracing in its construction my said improvement; Fig. 2 a longitudinal vertical section of the same; Fig. 3, a longitudinal horizontal section of the same, and Fig. 4 a
15 detail view.

In the drawings, A represents a box that is rectangular in form, except that each of its side pieces is sloped down from the point b nearly to a point at the front end of the bottom of the box where the front end of the bottom is turned up and bent back at an acute angle and made sharp, so that it may be forced into a heap of partially-burnt hard coal and ashes, and be thus filled with the same, acting thus after the manner of a scoop or a road-scraper.

20 B indicates a sheet of wire-netting of suitable size of mesh, extending from side to side and from end to end of the box, fastened to each side of the same, and having its front end inserted and fastened under the turned-up front edge of the bottom.

The sheet B at its front end rests upon the bridge-piece E, which extends across the bottom at that end of the box, and that bridge-piece serves to hold the sieve in position and to exclude ashes and coal from wedging themselves under its front edge in the operation of the device.

25 The sheet B is so fastened into position as to make an acute angle with the bottom of the box at the front end, and to rise from the front to the rear end, and thus furnish a chamber, F, for the ashes which will pass down through the sieve in the operation of the device.

The rear end of the box A is provided with guide-boards D, fastened in the corners thereof and extending up against the back end of the sieve, and they serve to guide the ashes falling through the sieve into and through the opening D' of the back end of the box into the hollow handle C, which is fastened to the rear

end of the box itself. The inner end of the handle C, where it is fastened to the box, is upon a level with the bottom of the same, but 55 it is made to incline upward at an angle with the same, as shown in the drawings, so as to form a trap which will prevent the escape of ashes during the operation of sifting, and thus I avoid the expense and trouble of a shutter to 50 close the outer end of the handle C; and for a like reason I have provided no means of closing the front opening of the box A, for my device is especially well adapted to sifting of the ashes from the unburnt coal immediately 55 at the ordinary heating-furnace where the ashes and coal may be scooped up out of the ash-pit, and the sifter shaken just within or immediately in front of the door thereof, in which case the check-damper to the furnace 70 will induce a constant current of air into the chimney sufficient to carry off with it any ashes that may rise during the operation of sifting, thus dispensing with all movable parts, such as doors, lids, and covers. 75

C indicates a brace having one of its ends attached to the hollow handle C, while the other end is attached to the box A, and is designed to stiffen and strengthen the handle C.

80 My whole device, except the wire-netting, is made preferably of galvanized iron sheets, and its parts are fastened together by means of rivets, and the joints are closed by the use of either solder or pressure.

The operation of the machine is quite simple. The operator takes the machine by the handle C, scoops up a portion of the ashes and coal, and shakes it in the usual manner, the ashes pass through the sieve while the coal remains upon it, and the ashes and coal being 90 completely separated, the end of the handle-spout C is placed upon the bottom of the hod or on the top of the accumulated heap of ashes previously deposited, and the entire apparatus is then brought to a vertical position, and 95 then the entire quantity of ashes in it will flow into the said spout-handle, whereupon the apparatus is gradually raised vertically and the ashes will spread out without being scattered in the form of dust. 100

In my pending application for Letters Patent for an improvement in ash-sifters, filed January 11, 1887, I have shown and described a device of different construction in several

respects, for use under different circumstances from those under which my herein-described device is best adapted to be used. The one described in the pending application is adapted 5 to use where there is no chimney-draft available—as, for instance, in the case of magazine-stoves—by which to carry off the ashes rising into the air during the operation of sifting, whereas the device described herein can be 10 used to equally good advantage where such drafts are available, and is much simpler in construction and operation.

What I claim as my invention, and desire to secure by Letters Patent, is—

- 15 1. The described box A, having a sheet of wire-netting, B, fastened to its sides above its bottom, and the opening D', in combination with the hollow handle C fastened thereto, substantially as and for the purpose described.
- 20 2. In combination with the box A, having two side pieces sloping at the front, and a bottom piece having its front edge turned up and back to form a sharp edge, the sieve B, having its side edges fastened to the side pieces of the box, and the bridge-piece E, resting on the bottom a little in the rear of the front edge thereof and under the front edge of the sieve, the front edge being adapted to be forced into

a heap of ashes while the bridge-piece will hold up the sieve from the bottom, substantially as 30 described.

3. The combination of the box A, the sieve B, having the guide-boards D and the opening D', and the hollow handle C, fastened to the rear end of the box, substantially as and for 35 the purpose described.

4. In combination with the box A, provided with guide-boards D, the sieve B, and the rear opening D', the hollow handle C, attached to the rear end of the box, having an 40 upward inclination thereto from its inner to its outer end, adapted to act as a trap to catch and hold the ashes during the operation of sifting, substantially as described.

5. The combination of the box A, having 45 the sieve B fastened therein, and an opening, D', in the rear end of the same upon a level with the bottom of the same adapted to sift the ashes from the coal, and to discharge them from under and from the rear end of the sieve, 50 substantially as described.

THOMAS SCHOLES.
